UNITED STATES PATENT OFFICE.

GEORGE RUSSELL, OF MCKEESPORT, PENNSYLVANIA.

CONDUIT.

No. 855,985.

Specification of Letters Patent.

Patented June 4, 1907.

Application filed August 22, 1906. Serial No. 331,661.

To all whom it may concern:

Be it known that I, GEORGE RUSSELL, a resident of McKeesport, in the county of Allegheny and State of Pennsylvania, have invented a new and useful Improvement in 5 Conduits; and I do hereby declare the following to be a full, clear, and exact description thereof.

My invention relates to conduits for electric wires, and has special reference to such conduits as are formed from metal tubing and provided with coatings to form smooth surfaces. Heretofore, in the manufacture of these conduits the tube was required to be 10 subjected to a pickling and a sand-blasting process, or to some other process, in order to provide the same with smooth surfaces and thereby overcome all liability of stripping the insulation off the wires in the running of 15 the same through the conduits. These pickling and sand-blasting processes were laborious and expensive and both would have a tendency to weaken the pipe or tube to a great extent, while the acid used in pickling 20 would also render the pipe or tube liable to become rusted and thereby spoil the same for the purpose intended. It also attacks 25 the threads on pipe and coupling thus making it almost impossible to get an absolutely 30 tight joint, and unless great care is exercised to remove all traces of the acid there is danger of it attacking and weakening the insulation of the wire.

The object of my invention is to do away 35 with these pickling and sand-blasting processes, thus permitting the use of a lighter weight stock for the pipe and at the same time provide a cheap, simple and efficient form of a conduit having the smooth surface 40 required.

My invention consists, generally stated, in the arrangement, construction and combination of parts, as hereinafter more specifically set forth, and described, and particularly 45 pointed out in the claims.

To enable others skilled in the art to which my invention appertains to construct and use my improved conduit for electric wires, I will describe the same more fully, referring to 50 the accompanying drawing, in which—

Figure 1 is a side elevation partly in section of a section of metal pipe or tubing showing my invention applied thereto. Fig. 2 is a cross-section of the tube. Fig. 3 is an end view of the same. Fig. 4 is a side elevation

partly in section of a tube section showing another manner of carrying out the invention. Fig. 5 is an end view of the lining showing it ready to be inserted into the tubing. Fig. 6 is a cross-section of the conduit 60 showing another form of the lining.

Like symbols of reference herein indicate like parts in each of the figures of the drawing.

As illustrated in the drawing, 1 represents 65 a piece of metal tubing for forming the conduit which is usually of iron or steel, and within such tubing is placed a lining 2. This lining 2 is tubular in form and is made from a thin and flexible sheet metal plate 3 having 70 an insulating coating 4 of enamel preferably on the face thereof which forms the interior surface of the lining, and such coating is of any suitable flexible enamel composition like that used in the manufacture of ferrotypes, 75 which is in the form of a liquid so that it can be applied to the plate and then baked into the same in any suitable manner of heating.

After the plate 3 has been cut in the proper width and length and coated in the above 80 manner it is rolled up into a tubular form and to size smaller than the interior of the tubing 1, as shown in Fig. 5, and while being held in this position it is inserted into and run through the said tubing to its proper position so that when it is released it will spring 85 out against the interior wall 1' of said tubing and form the lining 2 with the coated face 4 thereon forming the interior surface of said conduit. When the lining 2 is thus in place, 90 the protruding ends of the same are bent or flanged back against the ends of the tubing 1, as shown at 5, and the side edges 6 of the plate 3 in forming such lining 2 are so arranged as to width that they will about meet 95 or slightly overlap each other when the lining is in place within said tubing.

If it is desired, the side edges of the plate 3 can be flanged back at opposite positions to each other, as shown at 7 in Fig. 6, so that 100 when such plate is rolled up and is inserted into the tubing 1, the flanges 7 will interlock with each other when the plate is sprung out against said tubing and so form a lap-joint 105 therein. It will also be evident that the metallic plate 3 need not be coated with the flexible enamel composition at the time it is placed within the tubing 1 but such composition can be applied to the same after the metallic lining 2 is inserted and secured with- 110

in said tubing, by simply dipping the conduit into such composition and then baking the same into such conduit in any suitable manner and by the proper amount of heating. 5 This will form the coating 4 on the interior surface of the lining 2 and an outer coating 8 on the tubing 1, while the composition in the dipping of the conduit will also be enabled to run along the side edges 6 of the 10 lining and thereby form a tight joint and between the tubing and lining as well as under the flanges 5 in order to further protect and insulate the conduit.

Various other modifications and changes in 15 the construction, design and manner of forming my improved conduit may be resorted to without departing from the spirit of the invention or sacrificing any of its advantages. It will thus be seen that in my improved 20 conduit for electric wires there is provided a cheap and simple method of obtaining a tubing with a non-metallic coating thereon, and such coating on the interior of a metallic lining within such tubing will form a smooth 25 polished surface for fishing the wires through the conduit and for preventing all liability of injury to the insulation on such wires, while at the same time such coatings on the interior, exterior, and between the tubing and 30 lining will act as an insulator.

I am aware that it has been proposed that a metal tubing can be provided with an exterior and interior coating of zinc through an electrolytic process or electro - galvanizing 35 and that such electro-galvanized tubing is

provided with an interior coating of flexible material on said zinc coating.

I am also aware that a structure composed of a thin metallic pipe and having its interior galvanized and its exterior united to a composition covering placed upon the pipe by dipping the latter into the same or by placing the pipe in a mold and pouring the material therein, but—

What I claim as my invention and desire 45 to secure by Letters Patent is:

1. A conduit for electric wires comprising a metal pipe having a flexible metallic lining within the same and a flexible enamel coating on the inner surface of said lining. 50

2. A conduit for electric wires comprising a metal pipe having a thin flexible sheet metal lining within the same and a flexible enamel coating on the inner surface of said lining.

3. A conduit for electric wires comprising a metal pipe having a flexible metallic lining secured within the same and a flexible enamel coating on the inner surface of said lining. 55

4. A conduit for electric wires comprising a metal pipe having a thin flexible sheet metal lining secured within the same and a flexible enamel coating on the inner surface of said lining. 60

In testimony whereof, I the said GEORGE 65 RUSSELL have hereunto set my hand.

GEORGE RUSSELL.
